CLOTH DRYING APPARATUS

Camiel Malfet, Paterson, N. J.

Application September 22, 1930
Serial No. 483,403

2 Claims. (Cl. 158—104)

This invention relates to drying apparatus as used in treating textile fabrics, in piece lengths, by causing evaporation of superfluous moisture.

In the treatment of cloth in general and irrespective of its fibers, as silk, rayon, wool, ramie cotton or their combinations, and also its fabrication, as tightly woven, open mesh, long nap, pile, tufted, etc. etc., it is usually subjected to certain operations whereby its color, texture and weight are affected; as by fulling, shrinking, weighting, bleaching, dyeing and the like, during which the cloth is saturated and the liquids used partially absorbed, due to its immersion in vats containing the solutions.

18 In order to expedite the further operations, it is desirable to expel the excess moisture in the fabric by vaporization effectively, rapidly and uniformly.

Various types of devices have hitherto been 20 used for this purpose, such for instance as passing the goods over a highly heated rotating cylinder or drum, a fixed muffle, electrically heated coils or bars and open gas furnaces and it is to the latter type that the invention is directed.

25 To those familiar with the art it is well known that the step in finishing woven fabrics, known as drying, consists in tautly stretching the wet piece goods, as by automatically engaging its opposite edges with tentering devices carried on 30 travelling conveyor chains moved usually horizontally over a frame of very considerable length at a uniform rate of speed.

In the present embodiment a series of tubular 35 gas burners are disposed transversely below the path of the goods in such manner that the heat from the flames causes the excess moisture to vaporize and become dissipated in the atmosphere. It is also possible to use the apparatus for singeing filaments and fibers protruding from 40 the cloth in an effective manner.

One of the objects of the invention is to provide an apparatus in which the fuel gas used is delivered under a constant predetermined pressure and mixed with a proper proportion of air 45 to insure nearly perfect combustion.

A further feature is in the provision of means, including a motor driven pump, for compressing and delivering gas to the burners only when the motor is in actuation, the gas supply being closed 50 when the motor is stopped, and remote controls for the motor placed for convenience of an operator.

Another purpose is to produce a series of burners, each independently adjustable as to distance 55 from the fabric, provided with a central pilot

light burner fed from a separate source of gas supply and arranged to burn at full capacity only when the motor is stopped, its flame becoming reduced and blended with the main burner flames upon their gas supply becoming ignited to operate limit.

A characteristically valuable feature is to provide means to prevent any possibility of the pilot flame from depositing a sooty smudge on the fabric in passing over the burners, due to the fact that the pilot flame is lowered, almost to the point of extinguishment, during the operation of the burners.

These and other important features, such as simplicity and durability of parts, convenience 70 and ease of adjustment, and particularly the low cost of operation, due to the direct but safe application of heat, are attained by the novel construction, combination and arrangement of parts hereinafter described and shown in the 75 accompanying drawings, constituting a material part of this disclosure, and in which:—

Figure 1 is a side elevational view of a conventional cloth drying machine, largely diagrammatic, and showing an embodiment of the invention as applied.

Figure 2 is a side elevational view of a gas apparatus having a series of four burners drawn to an enlarged scale.

Figure 3 is a plan view of the same.

Figure 4 is an end elevational view of the apparatus, showing its position relative to the fabric undergoing operation, parts being broken away to show the structure of certain of its elements.

Referring in greater detail to the drawings, the view shown in Figure 1 is to be considered as representing a drying machine of very considerable length having at one end a pair of stands 15 provided with bearings adapted to rotatably receive a spindle 16 on which is coiled the fabric C to be treated.

The edges of the cloth are automatically engaged by tentering clamps 17 carried at short distances apart on endless conveyor chains guided by horizontal trackways 18 extending lengthwise at the tops of spaced frames, constituting the side members of the machine, the cloth being released to pass around rolls 19—19', carried on stands 20 at the front or delivery end of the machine, and delivered to be coiled on a roll spindle 21 removably journaled in bearings at the front of the stands.

The foregoing is briefly descriptive of the general type of drying machine with which the heat-

ing apparatus is used, but forms no part of the invention and is given, together with Figure 1, to show their relative proportions and relation.

The heating apparatus is preferably located 5 midway of the length of the drying machine and directly below the path of the cloth, which may travel at an average speed of approximately 500 feet per minute, depending on the character of the goods, moisture contained in the fibers and 10 results to be accomplished.

Each heating element, of which one or more, preferably four as shown, may be used consists 15 of a hollow standard 25, having an enlarged base, its upper portion being bored to receive a tubular support 26 having a clamp 27 by which the height of the support may be adjusted.

A packing gland 28, filling a counter bore in 20 the upper part of the main bore, is provided with extending flanges 28' through which pass bolts 29 also passing through corresponding flanges 25', to compress packing disposed around the body of the support, maintaining a gas tight joint.

At the upper end of the support is a head 30 25 bored at a right angle to the support to receive and firmly hold a tube 32 which may slightly exceed in length the width of the cloth C.

The head 30 and tube 32 contain communicating 30 passages open to the interior of the support 26.

A laterally extending projection 33 on the heads supports a small bent tube 34, one end of 35 which is directed downwardly adjacent the support and the other end curved to reach over the upper surface of the tube 32 where it is provided with a small burner 35 constituting a pilot light.

Set in a longitudinal slot in the tube 32 is a 40 metallic ribbon 36 provided with a multiplicity of fine perforations to act as burner openings when supplied with gas, which upon issuing is lit by the pilot light.

Both ends of the burner tube 32 are hermetically closed and mounted on the tube, near its ends, are split clamp collars 37, the upper elements 45 of which are provided with pairs of divergent arms 38 having between opposed pairs, guard rods 39, disposed above and out of the path of flame rising from the burners 36.

Above the bases of the standards 25 are opposed 50 bosses 40 having through openings 41, the bosses being drilled and tapped to receive pipes 42 rigidly connecting the several standards in spaced relation, the end standards having at their outer bosses caps 43—44, the latter being supplied with 55 an inlet pipe 45 connected by a union with the side opening in a reducer T 46 on a main gas supply pipe 47.

Set in each of the pipes 42, near one end, is a 60 nipple leading to a valve 48 and connected to the valve is a gas hose or flexible tube 49 leading to the down turned end of the pilot light tube 33 by which its burner is supplied with gas direct from the main supply source, each independently of the others and provided with an individual control valve.

The average pressure of gas from its supply 70 source, as a city main, is approximately 1 1/4 pounds per square inch, and while ample for the pilot lights, is insufficient for the main burners which, in order to obtain the best results, should be at an average of 2 1/2 pounds per square inch.

It is therefore necessary to raise the pressure 75 which is thus accomplished; in the main through opening of the T 46 is a pipe 50 leading to a pump 51 coupled direct with a motor 52 fixed on a plat-

form 53, preferably to one side of but closely adjacent the machine.

Here the gas pressure is raised by means of the pump controlled by a diaphragm device 54, the pressure being adjusted to suit by a lever 55, carrying adjustable weights 56, and delivered to a booster 57.

A pipe 60 provided with a cock 61, leads from the booster to a header or gas distributor pipe 62, preferable at the center of its length, and set 85 in the header, at points opposite the several standards 25, are service pipes 63 provided with valves 64, while at one end of the pipe 62 is a pressure gage 65, showing the fluctuations in gas pressure.

The end portions 63' of the pipes 63, are conically expanded and their extremities are threaded to engage in bosses 66 in the standards, at right angles and above the bosses 40, to communicate with chambers 67, closed from the openings 41, 95 but open to the plungers 26.

Adjustable vents 68 are provided on the pipes 63 for the admission of atmospheric air drawn in by the passing gas current to be mixed therewith on the way to the main burners 36.

It is to be understood that the motor pump, booster and fittings are commercial articles and that their specific construction form no part of the present invention.

The motor is controlled by push button 105 switches arranged in series, convenient to the operator, as at 70—71, on the stands 15—20 as indicated in figure 1, and it will be comprehended that when the motor is stopped the gas current flowing through pipes 60—62 ceases and therefore the 110 burners 36 cease to emit flames; at the same time, due to the virtual closing of the pipe 50, the pressure is increased in the pipes 42, causing the pilot burners 35 to produce maximum flames.

Obviously upon starting the motor the pressure 115 of gas leading to the pilot burners is reduced so that a low flame is maintained, and coincidently the pressure of gas in the pipes 62—62, standards 25, plungers 26 and main burner tubes 32 is boosted to the extent required, the 120 pressure being ascertained by the gage 65.

The inrushing current of gas through the pipes 63 sucks in air through the inlet 68 where it is intimately mixed with the gas in the expanded elements 63' and chambers 67, the mixture being delivered 125 to the burners 36, there to issue and become ignited by the pilot flames.

It may be noted that the apparatus described has demonstrated its efficiency and at a reduction of gas consumed amounting to 35% of the 130 quantity used in other devices for similar purposes.

The path of the cloth C is maintained at a fixed 135 height by the drying machine but the burners may be adjusted by the clamps 27 as to the distance below the cloth to suit varying conditions.

Should a break occur in the cloth, or any portion become loosened from the tenter clamps, it will ride over the rods 39 without becoming damaged and as the motor may be instantly 140 stopped, and hence gas to the burners, no material injury can occur to the goods, furthermore, and very important, is the fact that during the operation of the main burners, the pilot below is so low that no perceptible smoke issues to smudge 145 the fabric.

The foregoing disclosure is to be regarded as descriptive and illustrative only, and not as restrictive or limitative of the invention, of which 150 obviously an embodiment may be constructed.

including many modifications without departing from the general scope herein indicated and denoted in the appended claims.

Having thus described the invention, what is claimed as new and desired to secure by Letters Patent, is:—

1. In a cloth drying machine, a gas supply pipe having independent connections extending from one end thereof, a series of hollow standards each 10 having a partition therein dividing the same into upper and lower tubular chambers, pipe sections slidably mounted in the upper chamber and extending thereabove, tubular burners carried by said sections, said burners having a single straight 15 row of orifices, pilots carried on said burners centrally of the row of orifices, tubular sections rigidly connecting the base of the standards and communicating therethrough, said tubular sections being in communication with one connection 20 on said gas supply pipe, means connecting the other of said independent gas connections to the upper chamber in each of the standards, and flexible connections between said tubular sections and the pilots.
